[57] CLAIM

The ornamental design for a door mounting carrier for a track supported transaction security enclosure door, as shown and described.

DESCRIPTION

FIG. 1 is a perspective view of a door mounting carrier for a track supported transaction security enclosure door, embodying my new design, viewed from above and to the rear of the carrier;

FIG. 2 is a bottom front perspective view of the same; and

FIG. 3 is an end elevation view of the same, the opposite end elevation being the mirror image thereof.
